UNITED STATES PATENT OFFICE.

HERBERT J. SCHLUCKEBIER, OF FRANKENMUTH, MICHIGAN.

DESIGN FOR AN AUTOMOBILE-TIRE.

49,677.

Specification for Design.

Patented Sept. 19, 1916.

Application filed February 11, 1916. Serial No. 77,809. Term of patent 7 years.

To all whom it may concern:

Be it known that I, HERBERT J. SCHLUCKEBIER, a citizen of the United States, residing at Frankenmuth, in the county of Saginaw and State of Michigan, have invented a new, original, and ornamental Design for an Automobile-Tire, of which the following is a specification, reference being had to the accompanying drawing, forming part thereof.

Figure 1 is a plan view of a portion of an

automobile-tire, showing my new design. Fig. 2 is a side elevation thereof.

I claim:

The ornamental design for an automobile-tire, as shown.

HERBERT J. SCHLUCKEBIER.
